UNITED STATES PATENT OFFICE.

WILLIAM H. WOERHEIDE, OF ORANGE, NEW JERSEY.

FASTENING-STRIP FOR PREPARED ROOFING.

1,101,896.

Specification of Letters Patent. Patented June 30, 1914.

Application filed June 18, 1913. Serial No. 773,401.

To all whom it may concern:

Be it known that I, WILLIAM H. WOERHEIDE, a citizen of the United States of America, residing at Orange, in the county of Essex and State of New Jersey, have invented certain new and useful Improvements in Fastening-Strips for Prepared Roofing, of which the following is a full, clear, and exact description, reference being had to the accompanying drawings, forming a part of this specification.

My invention relates to fastening strips for securing sheets of prepared roofing upon foundations prepared therefor, the strips being adapted to be nailed onto the lap and butt joints of the roofing sheets.

The present invention has for its object the production of a sheet metal strip of this kind, which is of light weight and inexpensive nature, is arched transversely, and which is provided at intervals with nail holes extending through its crown, the strip being reinforced or strengthened inherently, to avoid the breaking down of its arch at or between the nailing points determined by nail holes in the crown of the strip.

I am fully aware that it is not broadly new to make arched sheet metal fastening strips for use in securing prepared roofing, strips of this kind having heretofore been in general use. As previously constructed, however, they could only be thoroughly satisfactory to resist the severe nailing strains and pressures, or effective in obtaining a uniformly firm binding pressure throughout the lengths of the strips along the laps of roofing, if made of very heavy metal, or provided at nailing points with auxiliary means to resist the strain and pressure incident to the driving of nails through and onto the crowns of the strips. Either the use of heavy sheet metal or the auxiliary strain resisting means at nailing points have heretofore been necessary for the reason that, otherwise, the arched strips would be mashed by the blows of a hammer in driving the nails, and either of these plans is impractical, owing to the expensiveness of the heavy metal, and the cost of manufacturing arched strips having auxiliary strain resisting means at the nailing points. In making my fastening strips, I utilize light and inexpensive sheet metal and obtain the desired uniformity of pressure

throughout the strips, with the sheet metal of the strips so strengthened or reinforced as to inherently resist the strains imposed thereon when driving nails through and onto the crowns of the strips. By so doing, 60 I am enabled to minimize the expense of manufacture of the strips, and make their use practical in every way, inasmuch as all needed requirements in fastenings of this kind are provided.

I am enabled by my present improvement to produce arched fastening strips from thin sheet metal, which contain the features of merit I have referred to, due to the sheet metal being drawn in a special manner, as 70 will be described, for reinforcement of the strip at the nailing points and, in addition to drawing the metal at these points, I permanently set it to prevent its return to its original position. By so drawing and permanently setting the sheet metal, I furnish such strips with highly strengthened and stiffened portions through which the nails are driven, thereby furnishing adequate resistance to pressures from the heads of nails 80 driven onto the crowns of the strips, or blows of hammers applied to such crowns at the nailing points. The drawing and permanent setting of the metal furthermore so stiffens and holds the metal at the nailing 85 points as to prevent pressure or strain thereat from being continued therefrom to the strips between nailing points, and as a consequence, distortion of the strips between nailing points is obviated. It should be 90 added further, that in producing my strips, the metal is so drawn as to draw the base flanges of the strips inwardly and upwardly, at nailing points, so that portions of the flanges at such points are narrowed relative to the portions of the flanges between nailing points, and occupy horizontal planes above the horizontal planes of the flanges between nailing points. By drawing metal to produce the described differential between the different portions of the base flanges of my strip, I place the flange portions at the nailing points approximately in alignment with the arch walls of the strip, so that when nails are driven through the 105 strip at the nailing points, the flanges thereat will be forced downwardly and become toed and embedded in the roofing sheets to such degree as to prevent spreading of the arch walls of the strip under nail 110

pressure. Furthermore, by the drawing of the sheet metal as set forth, and the provision of graduated wider and deeper flange portions between the nailing points, I provide for the flange portions between nailing points becoming seated upon the roofing sheets before the narrower and higher flange portions at nailing points are lowered to their seats by nailing operations with a very obvious result of causing the flanges to bear with uniform binding pressure upon the roofing sheets throughout the length of the strips.

To reinforce the sheet metal of my transversely arched thin metal fastening strip at the nailing points, I draw the sheet metal so as to produce dome-like swells extending upwardly from the crown of the strip, and continue the drawing action from said dome-like swells down, the side walls of the arch, with the result of providing narrow brace swells which converge from the dome-like crown swells into narrow lower ends directly at the bases of the arch walls. This arrangement of the brace and dome-like swells not only results in centering or confining the nailing pressure to points directly contiguous to the nail heads, but as the metal drawn to produce the swells is permanently set (or killed) at the bases of the drawn areas, the metal in the crown swells is prevented from returning to its former position. This condition is due to the permanent setting of the drawn metal creating a line of resistance at the junction of the crown swells and the metal around them.

Figure I is a top or plan view of a fragment of one of my roofing securing strips laid in position ready to be nailed upon the lap of two roofing sheets. Fig. II is an enlarged side elevation of a fragment of the strip as it appears before being nailed upon the roofing sheets. Fig. III is a greatly enlarged cross section taken on line III-III, Fig. II, through one of the reinforced nail receiving portions of the strip shown as it appears before a nail is driven therethrough to lower the strip by nail pressure. Fig. IV is a view similar to Fig. III, illustrating the reinforced portion of the strip in the lowered position assumed after a nail is driven therethrough. Fig. V is a greatly enlarged cross section taken on line V-V, Fig. II, illustrating the position of the portion of the strip between nailing points as it appears previous to the driving of nails through two adjacent nail holes. Fig. VI is a view similar to Fig. V, illustrating the position of the strip between nailing points as it appears after nails are driven through two adjacent nail holes.

In the accompanying drawings: A designates a sheet of prepared roofing and B a second sheet of prepared roofing lapped onto the sheet A. These roofing sheets are mounted

upon sheathing or other suitable foundation, as is common in the construction of roofs in which prepared roofing is used.

C designates one of my fastening strips, the strips being intended to be laid in series, preferably fitted together at their ends to provide overlapping joints. The strip C is arched transversely, thereby providing a crown 1 and side arch walls 2. At the bottoms of the arch walls are base flanges, which rest upon the roofing sheet the strip is applied to, and which are forced into firm and uniform binding contact with said sheet by the driving of nails through the strip at its crown, as will hereinafter more fully appear.

The fastening strip is made of thin sheet metal, and at the points where the nails are to be driven therethrough the metal of the strip is drawn, providing upstanding dome-like crown swells 3, these swells being perforated to furnish nail holes 3'. The metal of the strip is also drawn to provide outstanding brace swells 4, which continue downwardly from the dome-like crown swells 3 at the side arch walls 2, the latter swells converging from the crown swells into narrow lower ends which are located directly at the bases of the arch walls. In drawing the sheet metal to produce the coactive dome-like crown swells 3 and brace swells 4, I produce such displacement in the piece of sheet metal from which the strip is formed as to draw the base flange of the strip upwardly toward the crown 1 so that the base flanges are formed into portions 5, which are of less width and depth at the reinforcements provided by the crown and brace swells at which the nails are driven than the intermediate portions 6 of the base flanges located between nailing points. Furthermore, the flange portions 6 project laterally from the arch walls of the strip to a greater extent than the flange portions 5, at the nailing points the latter being drawn to positions that render them substantially aligned with the lower portions of the arch walls as seen in Figs. III and IV.

It will be obvious that by drawing a piece of metal in a manner to produce the swells 3 and 4 and in so doing narrow the base flange portions 5 relative to the flange portions 6, I furnish my strip with nail receiving members which, if they are prevented from assuming their former positions in the metal from which they were drawn, will adequately resist the pressure and strain imposed upon them by nails driven through the nail holes 3'. To prevent the return of the drawn metal present in the swells 3 and 4 to its former position, I permanently set the metal around or at the edges 7 of these swells by compressive strain, exceeding the limit of elasticity of the metal, which acts to create lines of resistance around the swells.

This permanent setting of the metal results in conferring an individuality upon the crown swells, and the downwardly extending convergent brace swells coactive with 5 the former. Consequently, when a nail is driven through a crown swell, the pressure of the head of the nail, when brought into contact with the crown swell, is directed through said crown swell, and then downwardly through the brace swells, so that such pressure is centered and confined to points directly contiguous to the nail heads, as hereinbefore mentioned, instead of such pressure being distributed through the fastening strip between nailing points, as it would be in the absence of the peculiarly formed pressure and strain resisting swells, and the permanent setting of the metal 10 around the swells, as explained.

20 In Figs. II, III and V, my strip is illustrated as it appears before nails are driven therethrough. It will be seen on referring to Figs. II and III that the base flange portions 6 of the strip rest upon the roofing sheet B, while the narrower base flange portions 5 are elevated therefrom. Figs. IV and VI illustrate the positions of the flange portions 5 and 6 after nails have been driven 25 through two adjacent nail holes, with the result of such nails forcing the strip downwardly at nailing points, as illustrated in Fig. IV. When two adjacent nails are driven, as mentioned, their heads, upon coming into impingement upon the crown swells 30 3, act to depress the fastening strip bodily, whereby the base flange portions 6 between nailing points are lowered into firm contact with the roofing beneath the strip, before the base flange portions 5 at the reinforced nailing points are brought into contact with such sheet. Thereafter upon continued driving of the nails, the base flange portions 5 are lowered to, and come into firm contact 35 with the roofing sheet. Furthermore, the flange portions 5, being extended downwardly in substantial alinement from the lower portions of the arch walls of the strip, become embedded and toed into the roofing sheet, and, by so doing act to overcome 40 spreading tendency of the arch strip, even under severe nailing pressure.

I claim:—

1. A sheet metal fastening strip arched transversely and having swells drawn from its crown, the metal at the edges of said 55 swells being permanently set to create lines of resistance around the swells.

2. A sheet metal fastening strip arched transversely and having swells drawn from its crown, the said swells being formed with 60 lateral downward brace extensions in the sides of the strip.

3. A sheet metal fastening strip arched transversely and having swells drawn from its crown, the said swells being formed with 65 lateral downward brace extensions in the sides of the strip, the metal at the edges of said swells being permanently set to create lines of resistance around the swells.

4. A sheet metal fastening strip arched 70 transversely and having swells drawn from its crown, the said swells being formed with lateral downward brace extensions tapering toward the bases of the arch walls.

5. A sheet metal fastening strip arched 75 transversely and having swells drawn from its crown, the said swells being formed with lateral downward brace extensions tapering toward the bases of the arch walls, the metal at the edges of said swells being permanently set to create lines of resistance around the swells.

6. A sheet metal fastening strip arched 80 transversely and having swells drawn from its crown, the said strip having flanges at 85 the bases of its side walls, the flanges being higher opposite said swells than between said swells.

7. A sheet metal fastening strip arched 90 transversely and having swells drawn from its crown, the said strip having flanges at the bases of its side walls, the portions of the flanges opposite said swells being substantially in alinement with the side walls of said strip adjacent their lower edges and being higher than the portions of the flanges 95 between the points at which said swells exist.

WILLIAM H. WOERHEIDE.

In the presence of—

ALBERT T. GUENTHER,
HARRY HOUSEL.
